CALCULATOR FOR DETERMINING HEATING AND COOLING REQUIREMENTS

Ragon E. Jones, 1201 E. Belle Cour Drive, Mobile, Ala.
Filed Oct. 21, 1958, Ser. No. 768,580

4 Claims. (Cl. 235—89)

This invention relates to a calculator for determining the amount of heating and cooling needed for residential housing.

The residential air conditioning industry, which includes heating and cooling, is presently hampered by the costly and time consuming methods used in estimating the sizes and capacities of heating and cooling units needed for houses of various sizes and types of construction. It is felt that the industry needs some means for accurately and quickly estimating such requirements.

In view of the above, it is a principal object of this invention to provide a calculator for determining the size of heating and cooling units needed for residential housing of various sizes and different types of construction.

It is another object to provide a calculator such as the above which is accurate and simple to use.

It is yet another object to provide a calculator as characterized by the above objects which is relatively inexpensive and easy to manufacture.

It is a still further object to provide a calculator as in the preceding objects which comprises a pair of cooperating slides carried within an envelope having two window openings for exposing at least portions of the respective slides.

The above and other objects will become more apparent when taken in conjunction with the following detailed description and drawings, showing by way of example a preferred embodiment of this invention, and wherein:

FIG. 1 is a top plan view of the calculator showing the two slides carried within the envelope and the two window openings exposing at least portions of the respective slides;

FIG. 2 is a plan view of a chart from which a value representing the ratio of glass area to floor area is determined; and

FIG. 3 is a horizontal cross sectional view taken along line 3—3 of FIG. 1.

As illustrated in FIGS. 1 and 3 the calculator 10 comprises a front sheet 12 and a back sheet 14 held in spaced relation by end spacers 16—16 and top spacer 18 shown in dotted lines in FIG. 1. The front and back sheets together with the end and top spacers form an envelope 20 having an open bottom slot indicated by arrow 22.

The front sheet 12 has a pair of rectangular windows 24 and 26. A scale representing floor area of a house is positioned on the front sheet 12 along the lower horizontal edge of the window 24. A pair of aligned slots 27—27 are formed in front and back sheets 12 and 14 respectively, adjacent and parallel to the vertical sides of window 24 to provide a pair of guideways 28, 28.

A pair of aligned slots 30—30 are cut in the front and back sheets 12 and 14 parallel to the outward vertical side of the window 26 to form a guideway 32. A slot 34 is cut in the bottom sheet 14 parallel to slots 30—30 to form a guideway 36 which is displaced inwardly of the inward vertical side of window 26.

A slide 40 is slidably carried within the envelope 20. This slide is retained in sliding alignment by means of pins 42, 42 carried in the slide and riding in guideways 28, 28. Slide 40 is generally rectangular in shape and includes a chart 44 adapted to register with window 24. This chart has plurality sloping lines having values derived from the ratio of glass area to floor area of a given house. These sloping lines intersect the scale on the lower horizontal edge of the window 24. Such intersection is controlled by the sliding back and forth of the slide 40. In

2

addition one vertical edge portion of the slide 40 extends under window 26. This edge portion has two index lines A and AA therein which represent two basic types of houses, namely, A for one-story and AA for two-story.

A second slide 50 is slidably carried within the envelope 5 20 in coplanar relation to the slide 40. This slide is retained in alignment by means of pins 52, 52 in the slide which ride in guideways 32 and 36. Slide 50 is generally rectangular in shape and contains a plurality of vertical scales. The first vertical scale, which is denoted by letters 10 A—F and AA—FF, relates to various types of house construction. The edge portion carrying the scale abuts the confronting edge of the slide 40 carrying index lines A and AA. In addition to the scale A—F and AA—FF, the slide 50 has two main divisions of scales one of one-story houses and the other for two-story houses. Each 15 of these main divisions contains two scales, one for heating requirements and one for cooling requirements. The scale for cooling requirements is divided into five columns, i.e., 10°, 15°, 18°, 20°, 25°. These values are known 20 as temperature differences and are well known in the art. The TD (temperature difference) depends on local conditions. Each cooling TD column has a scale representing tons of cooling capacity needed. The same arrangement is used in the heating scale, i.e., five TD columns namely 25 55°, 65°, 75°, 85°, 95°. Under each of these columns is a scale devoted to heat requirements in B.t.u.'s.

The lower horizontal edge of the window 26 is the result line, being so called because it is along this line that the values of the various scales are read to determine 30 heating and cooling requirements in accordance with the setting of slides 40 and 50.

Referring to FIG. 2, there is shown a chart 60 having a plurality of lines sloping upwardly and slightly diverging from left to right. The vertical scale represents glass 35 area of a house, while the horizontal scale represents floor area of the house. This chart is generally placed on the exposed face of the back sheet 14.

In using this calculator, the square feet of floor space and glass must be determined as well as the characteristics of the house such as, one or two stories, type of construction, i.e. brick, frame, etc., insulation if any, and also TD for heating and cooling in the particular area involved.

The first step is to refer to chart 60 shown in FIG. 2 and find the sloping line which intersects the point of intersection of the glass area and floor area on this chart. For example, assume the line R passes through this point. Further, assume that the house is one-story, the floor area 45 being 2,400 square feet. Slide 40 is next adjusted so that the sloping line R will intersect the 2,400 square feet designation on the scale on the lower horizontal edge of the window 24. Next, the slide 50 is adjusted so that index line A on slide 50 will line up with line A on slide 40. Now reference is made to the result line and to the proper columns to determine heating and cooling requirements. For example, suppose the TD for cooling is 18° and heating is 55°, then the requirements would be found 55 at points P and Q respectively.

The advantages of a calculator such as this will be readily apparent to people in the heating and cooling field. In a matter of minutes an estimate can be made, upon which prices can be approximated. Such a device is considered invaluable to estimators and salesmen in the field.

Having thus described my invention and the best mode of practicing the same, what I claim as novel and desire to secure by Letters Patent of the United States is:

1. A calculator for determining the heating and cooling requirements for housing of various sizes and construction, said calculator comprising a holder, first and second slides carried within said holder in coplanar rela-

tion so that one vertical edge of each slide abuts the other, the first slide having a plurality of sloping lines representing values derived from the ratio of glass to floor area, a scale on the holder representing floor area and adapted for alignment with said sloping lines to determine the position of the slide in the holder, said first slide having a pair of index lines on its vertical edge contacting the adjacent vertical edge on the second slide, said pair of index lines representing two different types of houses, the second slide having a first vertical scale representing various types of house constructions and positioned adjacent the vertical edge contacting the vertical edge of the first slide for alignment with one or the other of said index lines, said second slide also having a plurality of vertical scales representing heating and cooling requirements for either one or two-story houses for various temperature difference design characteristics, and the holder having a result line cooperating with the plurality of vertical scales on said second slide whereby when the second slide is positioned with its first vertical scale properly aligned with the index marks on the first slide the heating and cooling requirements for a specific house construction are read off the plurality of vertical scales where they intersect the result line.

2. The calculator as described in claim 1 wherein the holder comprises front and back sheets held in spaced relation by two end spacers and a top spacer to form an envelope having an open bottom.

3. The calculator as described in claim 2 wherein the front sheet of the holder has a pair of windows, the first window having the floor area scale positioned along its lower edge for alignment with the plurality of sloping lines on the first slide, and wherein the index lines on the first slide are exposed in the second window, the second slide being so positioned that all of the scales thereon are visible through said second window, and wherein said result line extends along the lower edge of the second window.

4. A calculator for determining the heating and cooling requirements for housing of various sizes and constructions, said calculator comprising a slide holder having front and back sheets held in spaced relation by two end spacers and a top spacer so as to form an envelope having its bottom open, the front sheet having a rectangular window with a scale representing square feet

of floor space extending along the lower horizontal edge of the window, a pair of parallel slots in the front and back sheets parallel to the vertical edges of the window, a rectangular slide slidably positioned within the envelope beneath the rectangular window, said slide having a plurality of sloping lines thereon representing the ratio of the glass area of a house to the floor area, and said slide being adapted for sliding so that the scale on the slide may be aligned with the horizontal scale on the lower edge of the rectangular opening, pins on the slide riding in the vertical slots in the front and back sheets to control the sliding movement of the slide, said slide having a pair of spaced index marks on one vertical edge portion designating different types of houses, the front sheet having a second rectangular window spaced from the first window, that portion of the first slide having the index lines being exposed in the second window adjacent the inward vertical edge thereof, aligned slots in the front and back sheets parallel and adjacent to the outward vertical edge of the second window, a second slide member slidably carried within the envelope with its inward vertical edge slidably abutting the adjacent vertical edge of the first slide, pin means on the second slide riding in the slots adjacent the second window to maintain alignment of the second slide, the second slide having a first vertical scale adjacent the vertical edge abutting the first slide, said second slide also having a plurality of vertical scales representing heating and cooling requirements for either one or two-story houses for various temperature difference design characteristics, the holder having a result line cooperating with the plurality of vertical scales on said second slide whereby when the second slide is positioned with its first vertical scale properly aligned with the index marks on the first slide, the heating and cooling requirements for a specific house construction are read off the plurality of vertical scales where they intersect the result line.
